UNITED STATES PATENT OFFICE.

HYMAN ELI GOLDBERG, OF CHICAGO, ILLINOIS, ASSIGNOR TO GOLDBERG CALCULATING MACHINE COMPANY, A CORPORATION OF ILLINOIS.

CALCULATING-MACHINE.

No. 893,721.

Specification of Letters Patent.

Patented July 21, 1908.

Application filed November 13, 1905. Serial No. 287,151.

To all whom it may concern:

Be it known that I, HYMAN ELI GOLDBERG, a citizen of the United States, residing at Chicago, in the county of Cook and State of Illinois, have invented a certain new and useful Improvement in Calculating-Machines, of which the following is a specification.

My invention relates to calculating machines and to calculating attachments to typewriters, and is, in the main, a divisional application from the one filed by me May 28, 1904 Serial No. 210,158. In that application I have shown as a modified structure but have not claimed in its specific form, a type of controlling mechanism in which the auxiliary setting wheels rotate whenever the valuating mechanism operates but are shiftable into two positions or stations in only one of which the auxiliary setting wheels are in line with, and hence operative upon, the receiving wheels of the receiving or totalizing mechanism.

The object of the present invention is to provide a machine in which the auxiliary setting wheel or wheels always rotate but do not always transmit the movement to the receiving wheels, such transmission depending upon whether the auxiliary setting wheel is shifted laterally to a position in line with or to a position not in line with one of the stopping points or stations of the receiving wheels.

Also in the former application I have shown a cam which co-operates with a spring to control the auxiliary setting wheel; the cam however is not positive in its action in the sense of being able unassisted to positively determine whether there shall be connection or non connection between the setting wheel and the totalizing mechanism. In this present application I have provided a double cam capable of occupying two positions in one position positively holding the setting means in connection with the totalizing mechanism and in the other position positively holding the setting means disconnected from the totalizing mechanisms, the action of the cam thus being positive in either circumstance.

I obtain my objects by the mechanism illustrated in the accompanying drawings in which:

Figure 1 is a general front view of my invention in the form of an attachment to a typewriter. Fig. 2 is a fragmentary sec-

tional view taken from front to rear of the machine and illustrating the relative positions of the framework, traveling carriage, totalizing mechanism and setting wheel. Figs. 3 and 4 are views chiefly in side elevation of the totalizing mechanism and adjacent parts. In Fig. 3 the controlling cam is shown in lowered position in which it shifts the setting wheel to active position. In Fig. 4 the cam is shown in raised position in which it holds the cam in non active position. Fig. 5 is a detail view illustrating the two possible positions of the controlling cam. Fig. 6 is an end view of the controlling cam. Fig. 7 is a plan view of the setting shaft with the setting wheels splined thereon. This figure illustrates the shifting action of the controlling cam and controlling lever. Fig. 8 is a front elevation of the splined setting shaft, the controlling mechanism and two receiving or totalizing mechanisms. The controlling cam is removed in order to illustrate the operative and non operative relationship between the setting wheels and the totalizing mechanisms. In the left side of Fig. 8 the setting wheel is shown to be out of line with the receiving wheels of the totalizer and hence non operative thereon and in the right side is shown to be in line with a receiving wheel and hence operative thereon. Fig. 9 is a side elevation of the machine partly in section illustrating among other things the escapement of the carriage. Fig. 10 is a fragmentary sectional view taken on the line 10—10 Fig. 9.

Similar numerals refer to similar parts throughout the several views.

Referring to the drawings, 1 represents the framework of a typewriter having a laterally shiftable carriage 2 and vertically movable keys 3. Although various forms of escapements may be employed, these mechanisms being well known in the art, a suitable one is indicated more particularly in Figs. 9 and 10 of the drawings. In the design selected for illustration the carriage is provided with a rack 40 rigidly fastened thereto in a line parallel with the direction of travel. This rack is engaged by a pinion 41 rigidly fastened to a shaft 42 pinioned in a bearing 43 upon the framework of the machine. Rigidly attached to shaft 42 is an escapement wheel 44 in position to co-operate with the two escapement dogs 45 and 46 which are pivoted

upon the stationary shaft or pin 47. These dogs are operated by a lever 48 connected to the universal bar 49 by means of the link 50. The universal bar is located in position to be operated by the different keys 3. The arrangement is such that when the keys are moved up and down the dogs 45 and 46 vibrate about their pivot shaft 47 as a center and permit the intermittent rotation of wheel 44. A spring (not shown) is employed to move the carriage one step each time it is released by the escapement dogs in the manner well known in the art. The numeral keys are connected in an appropriate manner to the valuating mechanism 4. The precise construction of said valuating mechanism is immaterial, its function being to drive shaft 5 and its attached pinion 6 different amounts depending upon the value of the key temporarily in action. The valuating mechanism here indicated is fully described in the patent issued to me February 14, 1905, No. 782,554.

Wheel 6, which may be termed the valuating pinion, rotates always in the same direction and is mounted in the stationary bracket 7 secured to bar 8 on framework 1. Said pinion is beveled and adapted to rotate the gear wheels 9 and 10 which are also beveled and mounted upon a common shaft 11 journaled in the said stationary bracket 7. Wheel 9 in addition to its bevel portion has a spur gear portion which is adapted to operate upon the totalizing mechanism; and as said gears 9 and 10 are located on opposite sides 35 of said valuating pinion they will be rotated in opposite directions and will therefore have opposite effects upon the totalizing mechanism as will hereinafter appear.

Shaft 11 is free to rotate in bracket 7, and 40 the main setting wheel 9 is loosely mounted on said shaft so as to rotate independently thereof. The bevel gear 10 is rigidly fixed on shaft 11 for the purpose of rotating it whenever said gear is rotated by the valuating pinion 45 6. Said shaft is splined, and on it are mounted sleeves 12, which are free to shift thereon lengthwise thereof, but always rotate when shaft 11 rotates. Rigidly attached to, and preferably integral with, the sleeves 12 are 50 the auxiliary setting wheels 13, which are adapted to mesh with the receiving wheels 14 of the totalizing mechanisms, as the latter travel past them. In this respect, the action is similar to the action described in my prior 55 patents Number 741,961, dated October 20, 1903, and the above-mentioned Patent No. 782,554 dated February 14, 1905, and in the said companion application Serial Number 210,158, filed May 28, 1904. In the present 60 instance, however, both the auxiliary setting wheels and the receiving wheels are thin enough and the receiving wheels are spaced a sufficient distance apart to permit the setting wheels to come between two adjacent 65 receiving wheels in the manner illustrated in

the left portion of Fig. 8, in which position the setting wheels will not engage the receiving wheels and the rotation of the setting wheels will not be imparted to them. Thus for a given position or station of the totalizing mechanism, an auxiliary setting wheel is capable of occupying two positions, in one of which it is in line with, and meshes with, a given receiving wheel, and in the other position is out of line with such receiving wheels 75 and is therefore out of engagement therewith.

The shifting of the setting wheels on their splined shaft is effected by means of shifting levers 15, which, in the present instance, are pivoted on the upright posts 16 on the brackets 7. Said levers are provided with pins 17 which are adapted to be received within the annular grooves 18 of sleeves 12 in such manner that when said levers are rotated about their pivots, said sleeves and the setting wheels 13 thereon will be shifted lengthwise of shaft 11 without interfering with the rotation of said sleeves and setting wheels. Said levers also have rigidly secured thereto pins 19 by which said levers are operated. In the present construction said pins 19 have heads 20 formed thereon, adapted to be engaged by the controlling cams 21.

As will hereinafter be mentioned, the totalizing mechanisms travel transversely to the plane of the setting wheels so as to bring the receiving wheels, one after the other, in position to be operated by the setting wheels.

In order to render the action of the machine positive without depending upon springs or similar devices in which there is always some possibility of error, the cam above mentioned is double; and in order to give the operator his choice as to whether an auxiliary setting wheel shall or shall not operate the receiving wheels as they pass by, said cam is so constructed as to be capable of occupying two positions in one of which it will cause the auxiliary setting wheels to assume an operative position and in the other of which it will cause said setting wheels to assume a non operative position relatively to the definite stations or rest points or stopping points of the receiving wheels of the totalizing mechanism. A suitable construction for a cam capable of obtaining my purpose is here shown, especially in Figs. 3, 4, 5 and 6. In the present design I have made it possible for said cam to assume two positions by pivoting the same upon the pins or trunnions 22 journaled in the side walls 23, 23, of the totalizing mechanism. A pin 24 is secured to one of said side walls 23 in such manner and in such position as to act upon the spring 24 upon cam 21 and retain it in the position in which it is set by the operator. The arrangement is such that when the cam is rotated to one or the other position by the operator, it will there remain until the position is al- 130

tered by the operator. Said cam is so constructed with reference to pin 19 and head 20 that when said cam is in lowered position as illustrated in Fig. 3 and in full lines, Fig. 5, the head 20 will be retained between the cam surfaces 25 and 26, while if the cam is rotated to raised position as illustrated in Fig. 4 and in dotted lines Fig. 5, said head 20 will be retained between the surfaces 27 and 26.^a

19 When within one of these pairs of surfaces the controlling lever 15 which carries the pin head 20 will be firmly and positively held in such position as to hold its setting wheel 13 in line with the stopping points of the receiving 20 wheels 14, and when said pin head is within the other of these pairs of cam surfaces on cam 21 lever 15 will be positively held in such position as to hold said setting wheel out of line with the stopping points of said receiving 25 wheels. It is thus evident that the action of the cam on the pin is positive in both positions of said cam. The ends of the cam are of course slightly beveled so that the cam surfaces will "find" the pin head upon coming up to it in the course of their travel.

For convenience, the form of totalizing mechanism here indicated is the one which is described in detail in my aforesaid patent No. 741,961, and also in the aforesaid companion application. The spirit of this invention, however, is not confined to this form of totalizing or receiving mechanism, for a totalizing mechanism equally suitable for use in the present machine is shown and described in Patent Number 782,605 issued to me February 14, 1905. Both of these totalizing mechanisms are reversible, that is, are adapted to add when the receiving wheels are rotated in one direction and to subtract when they are rotated in the opposite direction; but a non reversible receiving mechanism might be employed and yet permit the mechanism to accomplish some of the advantageous results of this invention; for example, if the setting wheel 9 were entirely omitted and only a single wheel 13 were employed, the cam device would still be operative to control such remaining wheel 13 to determine whether or not connection should be established between it and the totalizing mechanism and if two setting wheels 13 were employed, addition could be performed in the same horizontal line of typewriting, because said wheels 13, both rotate in the same direction.

In the present design, the manner of mounting the totalizing mechanisms and causing them to travel across the setting wheels is the same as that shown in my companion application and the aforesaid patents No. 741,961, and 782,554. Said totalizing mechanisms are mounted upon the slide 29 which is shiftable upon the guide-bar 8 hereinabove mentioned, said guide-bar running parallel to the direction of travel of the type-

writer carriage 2. The step by step movement of the carriage is imparted to said slide by means of the depending arm 30 extending from the carriage into the socket or keeper 31 on said slide 29.

The operation of the present machine is closely analogous to the operation of the one described in my aforesaid companion application, except that with the present device the auxiliary wheels 13 rotate every time the evaluating pinion 6 rotates. The carriage, of course, and, hence the totalizing mechanisms, travel from right to left with a step by step movement, the stopping points or station being definite and being the same each time the carriage repeats its journey. As the totalizing mechanism approaches in its usual direction of travel, it first reaches the main setting wheel 9, which rotates in, say, a positive direction to cause addition. If, now, the operator desires the auxiliary setting wheel to subtract out the same or a different number from the one set up by the main setting wheel, he throws cam 21 to such position that when it engages head 20, of pin 19, it throws lever 15 to such position that its auxiliary setting wheel 13 will be shifted to a point in line with one of the stopping points or stations of the receiving wheels of the totalizing mechanism. Inasmuch as the auxiliary setting wheels rotate in the opposite direction from the main setting wheel, it follows that whatever number is struck on the figure-keys will cause the rotation of the receiving wheels of the totalizing mechanism in a negative direction, and cause the subtraction of the number struck on the figure keys. Thus a difference will be shown on the totalizing mechanism. If the difference represents a positive number, the totalizing mechanism may then be cleared—that is to say, the wheels thereof may be returned to zero by printing that number at the side in such position that the receiving wheels will be in engagement with the second auxiliary setting wheel at the time of printing the number.

It will be evident that one, or more than one, auxiliary setting wheel may be employed in the machine, and that one or more than one totalizing mechanisms may be employed. It is also evident that one auxiliary setting wheel may be employed with one or more than one totalizing mechanism, and also that a plurality of auxiliary setting wheels may be employed with one or more than one totalizing mechanism.

What I claim as new and desire to secure by Letters Patent, is;

1. In a calculating machine the combination of a rotatable and shiftable setting wheel; a totalizing mechanism adapted to travel step by step across said setting wheel for coming into connection therewith, said totalizing mechanism stopping at definite stations in its step by step movement, and said

- setting wheel being shiftable to a point where its rotation will be transmissible to the totalizing mechanism at one of the stations thereof and to a point where its rotation will be 5 non transmissible to the totalizing mechanism at the same station thereof; and means traveling in unison with the totalizing mechanism for shifting said setting wheel to a predetermined one of its two described positions.
- 10 2. In a calculating machine the combination of a setting wheel adapted to rotate in two different lateral positions for each decimal place, a totalizing mechanism adapted to be operated thereby when said setting wheel is in one of its two lateral positions and not operated thereby when said wheel is in the other of its said two lateral positions, controlling means traveling relatively to one of the two first mentioned mechanisms for 15 shifting said setting wheel into a predetermined one of its two lateral positions, and mechanism for operating both the setting wheel and the said controlling means.
- 15 3. In a calculating machine the combination of a setting wheel adapted to rotate in two different lateral positions, for each decimal place a totalizing mechanism adapted to be operated thereby when said setting wheel is in one of its two lateral positions and not 20 operated thereby when said wheel is in the other of its said two lateral positions, controlling means traveling relatively to one of the two first mentioned mechanisms for shifting said setting wheel into a predetermined one of its two lateral positions, mechanism 25 for rotating said setting wheel, and mechanism for operating said traveling controlling means, the last mentioned two mechanisms having parts in common.
- 25 4. In a calculating machine the combination of a setting wheel adapted to rotate in two different lateral positions, for each decimal place a totalizing mechanism adapted to be operated thereby when said setting wheel is in one of its two lateral positions and not 30 operated thereby when said wheel is in the other of its said two lateral positions, controlling means traveling relatively to one of the two first mentioned mechanisms for shifting said setting wheel into a predetermined one of its two lateral positions, mechanism 35 for rotating said setting wheel, and mechanism for operating said traveling controlling means, the last mentioned two mechanisms having parts in common.
- 35 5. In a calculating machine the combination of a setting wheel and a totalizing mechanism one of which is adapted to travel relatively to the other for coming into coöperative relationship, said setting wheel being 40 laterally shiftable into two different positions for each decimal place and being adapted to rotate in both of its lateral positions, said setting wheel in one of its lateral positions being operative upon the totalizing 45 mechanism and in the other lateral position non operative upon said totalizing mechanism; and means traveling in unison with the part that travels for controlling the lateral position of said setting wheel.
- 50 6. In a calculating machine the combination of a setting wheel and a totalizing mechanism one of which is adapted to travel relatively to the other for coming into coöperative relationship, said receiving mechanism including a set of receiving wheels by which the totalizing mechanism is operated and said receiving wheels being located side by side and with a space between them greater than the width of said setting wheel; said setting wheel being laterally shiftable into two different positions and being adapted to rotate in both of its lateral positions, and said setting wheel in one of its lateral positions meshing with said receiving wheels and in 55 the other lateral position being out of mesh with and at the side of said receiving wheels; and means traveling in unison with the part that travels for determining the lateral position of said setting wheel.
- 60 7. In a calculating machine the combination of a setting wheel and a totalizing mechanism one of which is adapted to travel relatively to the other for coming into coöperative relationship, said totalizing mechanism including a set of receiving wheels by which the receiving mechanism is operated and said receiving wheels being located side by side and with a space between them greater than the width of said setting wheel; said setting wheel being laterally shiftable into two different positions and being adapted to rotate in both of its lateral positions, and said setting wheel in one of its lateral positions meshing with said receiving wheels and in 65 the other lateral position being out of mesh with and at the side of said receiving wheels; and a cam and a pin, one on the traveling and the other on the non traveling part for determining the lateral position of said setting wheel.
- 65 8. In a calculating machine the combination of a setting wheel and a totalizing mechanism one of which is adapted to travel relatively to the other for coming into coöperative relationship, said totalizing mechanism including a set of receiving wheels by which the totalizing mechanism is operated and said receiving wheels being located side by side and with a space between them greater than the width of said setting wheel, a splined shaft whereto said setting wheel is mounted so as to rotate therewith and shift laterally thereon to two different positions, one in line and in engagement with, and the other out of line and out of engagement with said receiving wheels; valuating means for rotating said shaft different amounts for setting up the digits; and means traveling in 70 unison with the traveling part of the ma-

chine for determining the lateral position of said setting wheel on its shaft.

9. In a calculating machine the combination of a setting wheel and a totalizing mechanism one of which is adapted to travel relatively to the other for coming into coöperative relationship, said setting wheel being laterally shiftable into two different positions and being adapted to rotate in both of its lateral positions, said setting wheel in one of its lateral positions being operative upon the totalizing mechanism and in the other non operative upon the totalizing mechanism; and a cam, and a pin coöperative there-
10 with, one of them on the traveling and the other on the non traveling part of the machine, and one of them being adapted to shift the setting wheel, and one of them being also adapted to be set in either of two differ-
15 ent positions, one position for shifting the setting wheel to one of the lateral positions thereof and the other position for shifting the setting wheel to the other of the lateral positions thereof.

20 10. In a calculating machine the combination of a setting wheel and a totalizing mechanism one of which is adapted to travel relatively to the other for coming into coöperative relationship, said setting wheel being laterally shiftable into two different positions and being adapted to rotate in both of its lateral positions, said setting wheel in one of its lateral positions being operative upon the receiving mechanism, and in the other lateral
25 position nonoperative upon said totalizing mechanism; a non traveling pin connected to said setting wheel for shifting the same, and a cam traveling in unison with the traveling part of the machine and adapted to operate
30 said pin for shifting said setting wheel, said cam being capable of occupying two positions for producing two different operative effects upon said pin and setting wheel.

35 11. In combination, a typewriter having a framework, a carriage shiftable relatively thereto, printing mechanism, keys for operating the same and shifting the carriage, a valuating mechanism operated by the same set of keys, a setting wheel connected to said
40 valuating mechanism and adapted to be always rotated thereby, a totalizing mechanism shiftable in unison with said carriage for coming into operative relation with said setting wheel, said setting wheel being shiftable into two positions, in one of which it is
45 in position to operate upon the totalizing mechanism, and in the other of which it is out of position to operate thereon; and controlling means for determining to which of
50 said two positions the setting wheel shall be shifted, said controlling means including a part connected to said setting wheel for shifting it and also including a second part
55 operative upon the first and traveling in
60 unison with the totalizing mechanism.

65 12. In a calculating machine the combination of a totalizing mechanism and setting mechanism, one of which is adapted to travel relatively to the other for coming into coöperative relationship, said setting mechanism including two setting wheels rotating in opposite directions and one adapted to operate the receiving mechanism after the other, one of said setting wheels being capable of occupying and rotating in two different positions
70 in one of which it is operated upon said receiving mechanism and in the other nonoperative thereon; and means traveling in unison with the traveling part of the machine for determining the position of the last men-
75 tioned setting wheel.

80 13. In combination, a typewriter having a framework, a carriage shiftable relatively thereto, printing mechanism, keys for operating the same and shifting the carriage, a valuating mechanism operated by the same set of keys, two non traveling setting wheels connected to said valuating mechanism to rotate in opposite directions at each action
85 of said valuating mechanism, a receiving mechanism shiftable in unison with said carriage for coming into operative relation with one of said setting wheels after the other, one of said setting wheels being shiftable into two positions in one of which it is operative
90 upon the receiving mechanism at one of the points of rest thereof and in the other of which it is not operative upon said receiving mechanism at any of the points of rest thereof, and controlling means for determining to
95 which of said two positions the setting wheel shall be shifted, said controlling means consisting of a cam and pin mechanism operative upon said setting wheel to shift it, one of the parts of said controlling device being
100 connected to and traveling with the typewriter carriage.

105 14. In a calculating machine the combination of a totalizing mechanism; a valuating mechanism one being shiftable so as to travel relatively to the other; means for connecting them; and a hand adjustable device for positively rendering said connecting means operative or non operative, part of said hand adjustable device being stationary and part
110 traveling in unison with the traveling portion of the machine, for bringing the said two parts into coöperative connection whereby said hand adjustable device is non operative except when its traveling part has traveled
115 to a point in juxtaposition to the laterally fixed part of said device, and while thus in juxtaposition renders the connecting means either operative or nonoperative; depending upon the condition to which said hand adjustable device is adjusted.

120 15. In a recording calculating machine the combination of a paper platen; means for printing on the same; totalizing mechanism; and a setting wheel for operating said total-
125

izing mechanism, said setting wheel being adapted to operate said totalizing mechanism when said printing means is in position to print in a predetermined column; means for driving said setting wheel to thus operate the totalizing mechanism; means for making and breaking the operative connection between said driving means and said totalizing mechanism, said making and breaking means being hand adjustable whereby it will when in one position make said connection and in the other position break said connection between said driving means and said totalizing mechanism, said making and breaking means being operative only when said platen is laterally in position to be printed upon in said pre-determined column.

16. In a calculating machine the combination of a totalizing mechanism including receiving wheels; a setting wheel for operating the same, one being shiftable relatively to the other, said setting means being adapted to operate said totalizing mechanism when in apposition to the receiving wheels thereof and non operative when in non apposition with said receiving wheels; valuating means for driving said setting wheel; and other means for making and breaking the operative connection between said valuating means and said totalizing mechanism, part of said making and breaking means being hand adjustable whereby it will when in one position make said connection and in the other position prevent the connection between said setting wheel and said totalizing mechanism, part of said making and breaking means traveling with the traveling part of the machine.

17. In a calculating machine, the combination of a totalizing mechanism; a setting member; and means controlled by said totalizing mechanism for either making or breaking the operative connections between said totalizing mechanism and said setting member.

18. In a calculating machine, the combination of a totalizing mechanism and a setting wheel operative upon said totalizing mechanism, means for driving said setting wheel; and means upon said totalizing mechanism for bringing said setting wheel into position to be operative or into position to be non operative upon said totalizing mechanism.

19. Mechanism for connecting a totalizing mechanism with its operating mechanism including a part capable of occupying two positions, in one position positively holding the operating mechanism in connection with the totalizing mechanism and in the other posi-

tion positively holding the operating mechanism out of connection with the totalizing mechanism.

20. Mechanism for connecting a totalizing mechanism with its operating mechanism including a cam and pin device one of the parts whereof is capable of occupying two positions, in one position positively holding the operating mechanism in connection with the totalizing mechanism and in the other position positively holding the operating mechanism out of connection with the totalizing mechanism.

21. In a calculating machine, mechanism for connecting a totalizing mechanism with its operating mechanism including a double cam capable of occupying different positions, in one position positively holding the totalizing and operating mechanisms in connection with each other, and said cam in another position positively holding said totalizing and operating mechanisms out of connection with each other.

22. In combination, a totalizing mechanism and operating means therefor one of which travels relatively to the other; and mechanism, including a piece which travels in unison with the traveling part of the machine, for establishing the connection between the totalizing mechanism and operating means, said traveling piece being capable of occupying two positions, in one position positively holding the operating mechanism in connection with the totalizing mechanism, and in the other position positively holding the operating mechanism out of connection with the totalizing mechanism.

23. In combination, a totalizing mechanism; operating means therefor; and mechanism including a part which travels in unison with the traveling part of the machine, for establishing the connection between the totalizing mechanism and the operating means, one of the pieces of the establishing mechanism being capable of occupying different positions, in one position positively holding the operating mechanism in connection with the totalizing mechanism and in the other position positively holding the operating mechanism out of connection with the totalizing mechanism.

In witness whereof, I have hereunto subscribed my name in the presence of two witnesses.

HYMAN ELI GOLDBERG.
